(57) **CLAIM**

The ornamental design for a clip for attaching a cylindrical object to a belt or a waistband, as shown and described.

DESCRIPTION

FIG. 1 is a front elevation of a clip for attaching a cylindrical object to a belt or a waistband, showing the design;

FIG. 2 is a right elevation thereof, with the left elevation being a mirror image of the right elevation;

FIG. 3 is a rear elevation thereof;

FIG. 4 is a top plan view thereof; and,

FIG. 5 is a bottom plan view thereof.
